SHELF BRACKET

Paul F. Simpson, Oakville, Conn., assignor to The
Autoyre Company, Oakville, Conn., a corpora-
tion of Connecticut

Application March 21, 1950, Serial No. 8,674

Term of patent 14 years

(Cl. D33—3)

To all whom it may concern:

Be it known that I, Paul F. Simpson, a citizen of the United States residing in Oakville, State of Connecticut, county of Litchfield, have invented a new, original, and ornamental Design for Shelf Bracket, of which the following is a specification, reference being had to the accompanying drawing, forming a part thereof.

In the drawing,

Fig. 1 is a perspective view of a shelf bracket showing my new design;

Fig. 2 is a side view of the bracket; and

Fig. 3 is a top plan view thereof.

The dominant features of my new design have been illustrated in the drawing in full lines.

I claim:

The ornamental design for a shelf bracket, substantially as shown and described.

PAUL F. SIMPSON.
